DESIGN FOR A LENS OR SIMILAR ARTICLE

George M. Cressaty, New York, N. Y.

Application May 6, 1943, Serial No. 110,133

Term of patent 14 years

To all whom it may concern:

Be it known that I, George M. Cressaty, a citizen of France, residing at New York, in the county of New York and State of New York, have invented a new, original, and ornamental Design for Lens or Similar Article, of which the following is a specification, reference being had to the accompanying drawing, forming part thereof.

Fig. 1 is a plan view of a lens or similar article embodying my new design;

Fig. 2 is a sectional view thereof substantially on the line 2—2 of Fig. 2; and

Fig. 3 is a bottom plan view thereof.

I claim:

The ornamental design for a lens or similar article, substantially as shown.

GEORGE M. CRESSATY.
